UNITED STATES PATENT OFFICE.

BENONA MAGNUS FARLEY, OF HAMLINE, MINNESOTA.

DESIGN FOR A FOOT-REST FOR BICYCLES.

SPECIFICATION forming part of Design No. 24,177, dated April 2, 1895.

Application filed December 24, 1894. Serial No. 532,889. Term of patent 7 years.

To all whom it may concern:

Be it known that I, BENONA MAGNUS FARLEY, a citizen of the United States, residing at Hamline, in the county of Ramsey and State 5 of Minnesota, have invented and produced a new and original Design for a Foot-Rest, of which the following is a specification.

Reference is to be had to the accompanying drawings, in which—

10 Figure 1 is a perspective view of a foot rest embodying my new design; and Fig. 2 is a side elevation thereof, in inverted position.

The leading feature of my design consists in the foot rest having the configuration shown, 15 to wit: the cylindric cross bar *a*, the foot plate *b* disposed tangentially to the cross bar, the side edges of said plate narrowing and being upturned as at *b'*, the lines of said plate

tapering both toward the front and rear, the taper being more pronounced toward the 20 front; and the narrow plate *c* disposed longitudinally of the plate *b*, said plate *c* lying parallel at its rear end with the plate *b*, as at *c'*, then bridging the cross bar *a*, as at *c²*, then ranging parallel with plate *c* again in front of 25 the cross bar and projecting beyond the front of plate *c*, and finally returned on itself in hook form as at *c³*.

I claim—

20 The design for a foot rest herein shown and 30 described.

BENONA MAGNUS FARLEY.
